SHOE REST MECHANISM

Fred C. Eastman, Beverly, Mass., assignor to
United Shoe Machinery Corporation, Paterson,
N. J., a Corporation of New Jersey

Application April 8, 1931. Serial No. 528,610

27 Claims. (Cl. 12—123)

This invention relates to machines for use in the manufacture of shoes, and more particularly to shoe rest mechanism forming part of such a machine. The invention is herein illustrated in its application to mechanism for supporting the forepart of a shoe against pressure applied on its bottom face in the lasting of the toe end of the shoe, but it is to be understood that it is not limited to mechanism that acts in that particular manner or in that particular relation to a shoe nor limited to machines for lasting shoes.

In a copending application of Fred N. LaChapelle, Serial No. 440,834, filed on April 1, 1930, there was disclosed a novel shoe rest for the top of the forepart of a shoe, comprising a group of members mounted in a holder and relatively movable to conform to the contour of the shoe in response to pressure of the shoe thereon resulting from relative movement of the shoe and the holder, together with means controlled by the operator for thereafter securing the members in fixed relation to the holder to provide a firm support for the shoe. An object of the present invention is to provide improvements in shoe rest mechanism of that general nature, and more particularly in the means whereby the relatively movable members are secured in fixed relation to their holder after their conformity to the contour of the shoe. For the purposes in view, in one novel aspect, the invention accordingly provides means constructed and arranged to operate in automatically determined time relation to the relative movement of the shoe and the holder to secure the members in fixed relation to the holder, thus affording not only such advantages as arise from the elimination of a manual operation, but also increased insurance that the members will be held in a uniformly effective manner in operating on different shoes. In the construction herein illustrated, in which the holder is moved to press the members into conformity to the top of the forepart of the shoe, there is provided toggle mechanism which acts in automatically determined time relation to the movement of the holder toward the shoe to clamp the members against one another and against the holder.

In a further aspect, the invention provides novel means for holding or securing a shoe rest as a whole against movement in response to pressure of a shoe thereon, the construction shown comprising means whereby the holder in which the above-mentioned relatively movable members are mounted is clamped against a relatively stationary part of the machine to hold it

frictionally against reverse movement after its movement toward the shoe. As illustrated, the holder is thus clamped and held by the action of the same means that clamps the relatively movable members against one another and against the holder.

The above and other features of the invention, including also novel details of the holder for the relatively movable shoe rest members and various other novel details of construction and combinations of parts, will now be more particularly described by reference to the accompanying drawings and pointed out in the claims.

In the drawings,

Fig. 1 is a view partly in elevation and partly in section showing portions of a machine in which the invention is embodied;

Fig. 2 shows in elevation a portion of the structure as viewed from the left-hand side of Fig. 1;

Fig. 3 is a plan view, with parts broken away; and

Fig. 4 shows partly in elevation and partly in section another portion of the structure as viewed from the left-hand side of Fig. 1.

The invention is herein illustrated as applied to a toe-lasting machine the general organization of which is disclosed in Letters Patent No. 1,918,274, granted on July 18, 1933, upon an application of F. N. LaChapelle and F. C. Eastman. Only such portions of the machine, therefore, as it is necessary to refer to for an understanding of this invention are herein shown and will be described in detail.

The machine includes toe-embracing wipers 10 which are operated to wipe the margin of the toe end of the upper inwardly over an insole on the last and to press it upon the insole, and upper-fastening mechanism comprising a guide 12 for a gang of fastenings and their drivers which is moved into operative position in front of the edges of the wipers, as illustrated in Fig. 4. The position of the last and shoe in relation to the lasting means is determined by a plurality of pins 14 fast on a plate 16 secured to a fixed arm 18, these pins being arranged to project through holes in the insole into sockets formed in metal bushings 19 in the last. The pins 14 serve as means against which the last is pressed upward and held firmly to support it against pressure applied on the bottom of the shoe in the lasting operation.

For supporting the last and shoe in the manner above described the machine is provided with a shoe rest arranged to engage the shoe on the top

of the forepart and having features in common with the disclosure of the above-mentioned LaChapelle application Serial No. 440,834. This shoe rest comprises a plurality of small metal rods 20 arranged in parallel and contiguous relation to one another in a group extending both lengthwise and laterally of the shoe with the upper ends of the rods directed toward the top of the forepart of the shoe, the lower ends of the rods 10 resting upon a soft rubber pad 22 which permits them to move lengthwise relatively to one another in response to pressure of the shoe on their upper ends and thus to conform to the contour of the top of the forepart of the shoe. 15 Mounted on the upper ends of the rods is a cap 24 of thin flexible leather which prevents direct contact of the rods with the shoe. The rods are confined in a holder comprising three side plates 26, 28 and 30 arranged in triangular relation and supported on a horizontal plate 32 having a hollow depending stem detachably mounted on the upper end of a rod 34. The plate 32 serves also as a support for the rubber pad 22 which is confined by the side plates. In the construction 25 herein shown the plates 26 and 28 are integral with each other and are secured in fixed relation to the plate 32, while the plate 30 is movable relatively to the other plates to clamp and secure the rods 20 in fixed relation to one another and to their holder after they have conformed to the 30 contour of the shoe. To render the clamping pressure more effective, also, the construction shown is such that the group of rods is not extended to the apices of a triangle, but has a hexagonal formation, the plates 26 and 28 being shaped to give the group this form at one corner of the triangular holder and movable wedge-shaped clamping pieces 36 and 38 being inserted 35 for the same purpose at the other two corners. It will be observed that the plate 30 has portions that overlap respectively an edge of the plate 26 and a side face of the plate 28 to guide it in its movements to clamp and release the rods. 40 It will be understood that initially the shoe rest is in a lower position than indicated in the drawings, to permit the last and shoe to be mounted on the pins 14, and that it is moved upwardly to press the rods 20 into conformity to the 45 contour of the shoe and to serve thereafter as a support for the shoe. For this purpose the rod 34 is mounted for vertical movements in bearings in the frame of the machine and is moved upwardly by a sleeve member 40 which is slidably movable on the rod and acts through a spring 42 on a collar 44 fast on the rod. The sleeve member 40 acts on the spring through a collar 46 which is slidably movable on a reduced portion of the rod 34 and is arranged to rest on a shoulder 50 50 on the rod when the parts are in starting positions. The sleeve member 40 is connected at its opposite sides by links 50 to the forked end of a lever 52 pivoted on the frame of the machine and connected by a link 54 to a crank pin 56 carried by a gear wheel 58 which is fast on a power-operated shaft 60. As disclosed in the above-mentioned Letters Patent, the shaft 60 is operated through clutch-controlled mechanism whereby it is turned through a half revolution at each 55 actuation of the clutch. Accordingly, upon one actuation of the clutch, the shoe rest is moved upwardly into supporting engagement with the shoe, and upon a second actuation of the clutch, after the lasting operations have been performed, it is 60 returned to its starting position.

For purposes of this invention the machine is provided with mechanism that operates in automatically determined time relation to the movement of the shoe rest toward the shoe to impart to the plate 30 movement to clamp the rods 20 in fixed relation to one another and to their holder after they have conformed to the contour of the shoe. This mechanism includes a cylindrical member 62 mounted for turning movement about a vertical axis in a bearing in the frame of the machine and having its upper portion so shaped as to provide an eccentric shoulder 64 arranged to bear on a lug 66 projecting from the plate 30, this shoulder being elongated vertically to permit the upward and downward movements of the shoe rest while maintaining a close relation at all times to the lug 66. Clamped on the lower end of the member 62 is an arm 68 which is operated by a toggle comprising two links 70 and 72 connected together by a pin 74, the link 70 being connected to the arm 68 by a ball and socket joint and the link 72 being mounted on a pin 76 in the frame of the machine. The link 70 comprises two portions which are threaded together and relatively adjustable to vary the clamping pressure on the rods 20. The toggle is operated through a link 78 connected to the pin 74 and having fast thereon two collars 80 and 82 between which is slidably mounted a sleeve member 84 connected by an arm 86 to a pin 88 where- 100 by one of the previously-mentioned links 50 is connected to the sleeve 40. It will thus be seen that the sleeve member 84 is operated by the lever 52 as this lever is moved to impart to the shoe rest rod 34 its upward movement. The collars 80 and 82, however, are spaced apart to provide for such lost motion as to permit the shoe rest to be raised and pressed firmly against the shoe prior to the application of any substantial clamping pressure to the rods 20. As soon as the sleeve 84 engages the collar 80 it begins to raise the link 78, and during further compression of the spring 42 the link is operated to straighten the toggle 70, 72 and thus to turn the member 62 so that its shoulder 64 imparts 110 clamping movement to the plate 30. At the end of this operation the toggle is substantially straight, as illustrated in Fig. 1, and the shoe rest rods 20 are clamped firmly against one another and against their holder to prevent them from 115 moving relatively to the holder in response to pressure of the shoe thereon in the lasting operation. 120 In order to maintain the shoe rest in position to serve as a firm support for the shoe it is necessary also to prevent any downward movement of the above-mentioned holder and its supporting rod 34 in response to pressure of the shoe on the shoe rest. For this purpose the invention, 125 in its illustrated embodiment, further provides means whereby the holder is clamped to hold it frictionally against any downward movement. This means comprises a rib 90 projecting from the plate 26 of the holder and having the form of a wedge with converging side faces extending 130 into a corresponding opening formed in a member 92 which is fast on the frame of the machine, this member having faces arranged for clamping engagement with the faces of the rib 90. It will be observed that the wedge faces on the rib 90 and the cooperating faces on the member 92 extend in parallel relation to the direction of movement of the shoe rest, so that the clamping means will act with the same effectiveness regardless of the position of the shoe 135 140 145 150

rest. Conveniently the rib 90 is clamped against the member 92 by the action of the same eccentric shoulder 64 that imparts to the plate 30 its movement to clamp the rods 20, this shoulder 5 accordingly acting as a clamp member at the opposite side of the shoe rest from the member 92, and also assisting by frictional contact with the lug 66 in holding the shoe rest against downward movement. It will be understood that the 10 rib 90 is at all times substantially in contact with the member 92 so that it may be firmly clamped against this member by a negligible amount of lateral movement of the shoe rest holder permitted by play of the plate 32 on the rod 34 and 15 of the rod 34 in its bearings. This retaining means takes the place of pawl-and-ratchet mechanism heretofore provided for supporting the shoe rest and insures that the latter will be held precisely in any position to which it is moved in 20 clamping a shoe. It will be evident that the member 92 also acts as an abutment to support the shoe rest against the rod-clamping pressure applied to the plate 30.

Having described the invention, what I claim 25 as new and desire to secure by Letters Patent of the United States is:

1. In a shoe machine, a shoe rest comprising a group of members relatively movable in response to pressure of a shoe thereon to conform to the 30 contour of the shoe, a holder for said members, means for effecting relative movement of said holder and the shoe to cause the members to conform to the contour of the shoe, and mechanism constructed and arranged to operate in 35 automatically determined time relation to said relative movement to secure the members in fixed relation to the holder.

2. In a shoe machine, a shoe rest comprising a group of members arranged in contiguous relation 40 to one another and relatively movable in response to pressure of a shoe thereon to conform to the contour of the shoe, a holder in which said members are mounted, means for effecting relative movement of said holder and the shoe to cause the members to conform to the contour of 45 the shoe, and mechanism constructed and arranged to operate in automatically determined time relation to said relative movement to clamp the members against one another and against the holder.

3. In a shoe machine, a shoe rest arranged to engage a shoe on the top of the forepart, said shoe rest comprising a group of parallel rods extending heightwise of the shoe in contiguous relation to one another and relatively movable in 55 response to pressure of the shoe thereon to conform to the contour of the shoe, a holder in which said rods are mounted, means for effecting relative movement of said holder and the shoe to cause the rods to conform to the contour of the shoe, and mechanism constructed and arranged to operate in automatically determined time relation to said relative movement to clamp the rods against one another and against the holder. 60

4. In a shoe machine, a shoe rest arranged to engage a shoe on the top of the forepart, said shoe rest comprising a group of members relatively movable in response to pressure of the shoe thereon to conform to the contour of the shoe, a holder in which said members are mounted, means for moving said holder toward the shoe 70 to cause the members to conform to the contour of the shoe, and mechanism for securing said members in fixed relation to the holder in auto-

matically determined time relation to the movement of the holder.

5. In a shoe machine, a shoe rest arranged to engage a shoe on the top of the forepart, said shoe rest comprising a group of members relatively movable in response to pressure of the shoe thereon to conform to the contour of the shoe, a holder for said members comprising parts relatively movable to clamp the members in fixed relation thereto, a device for moving the holder toward the shoe to cause the members to conform to the contour of the shoe, and mechanism arranged to be operated by said device in predetermined time relation to the movement of the holder to effect the relative clamping movement of parts of the holder. 80

6. In a shoe machine, a shoe rest arranged to engage a shoe on the top of the forepart, said shoe rest comprising a group of members relatively movable in response to pressure of the shoe thereon to conform to the contour of the shoe, a holder for said members comprising parts relatively movable to clamp the members in fixed relation thereto, means for moving the holder toward the shoe to cause the members to conform to the contour of the shoe, and toggle mechanism constructed and arranged to operate in predetermined time relation to the movement of the holder to effect the relative clamping movement of parts of the holder. 90

7. In a shoe machine, a shoe rest arranged to engage a shoe on the top of the forepart, said shoe rest comprising a group of members relatively movable in response to pressure of the shoe thereon to conform to the contour of the shoe, a holder for said members comprising parts relatively movable to clamp the members in fixed relation thereto, a device for moving said holder toward the shoe to cause the members to conform to the contour of the shoe, mechanism for effecting relative clamping movement of parts of the holder, and a lost-motion connection between said device and mechanism to cause the clamping of the group of members after a predetermined movement of the holder toward the shoe. 100

8. In a shoe machine, a shoe rest arranged to engage a shoe on the top of the forepart, said shoe rest comprising a group of members relatively movable in response to pressure of the shoe thereon to conform to the contour of the shoe, a holder for said members comprising parts relatively movable to clamp the members in fixed relation thereto after their conformity to the contour of the shoe, and an eccentric member arranged at one side of the holder and rotatable about an axis extending heightwise of the shoe to effect the relative clamping movement of parts of the holder. 110

9. In a shoe machine, a shoe rest arranged to engage a shoe on the top of the forepart, said shoe rest comprising a group of members relatively movable heightwise of the shoe in response to pressure of the shoe thereon to conform to the contour of the shoe, a holder for said members comprising parts relatively movable to clamp the members in fixed relation thereto after their conformity to the contour of the shoe, a member rotatable about an axis extending heightwise of the shoe and arranged to act on said holder to effect the relative clamping movement of the parts, and a toggle for operating said rotatable member. 120

10. In a shoe machine, a shoe rest arranged to engage a shoe on the top of the forepart, said shoe rest comprising a plurality of members rela- 130

- tively movable heightwise of the shoe in response to pressure of the shoe thereon to conform to the contour of the shoe, and a holder of substantially triangular shape in which said members are mounted, different triangularly arranged sides of said holder being relatively movable to clamp the members in fixed relation to the holder after they have conformed to the contour of the shoe.
10. 11. In a shoe machine, a shoe rest arranged to engage a shoe on the top of the forepart, said shoe rest comprising a plurality of members relatively movable heightwise of the shoe in response to pressure of the shoe thereon to conform to the contour of the shoe, and a holder of substantially triangular shape in which said members are mounted, two of the three sides of said holder being arranged in fixed relation to each other and the third side being movable relatively to the other two sides to clamp the members in fixed relation to the holder after they have conformed to the contour of the shoe.
15. 12. In a shoe machine, a shoe rest arranged to engage a shoe on the top of the forepart, said shoe rest comprising a plurality of members relatively movable heightwise of the shoe in response to pressure of the shoe thereon to conform to the contour of the shoe, and a holder of substantially triangular shape in which said members are mounted, the other two sides to clamp the members in fixed relation to the holder after they have conformed to the contour of the shoe.
20. 13. In a shoe machine, a shoe rest arranged to engage a shoe on the top of the forepart, said shoe rest comprising a plurality of members relatively movable heightwise of the shoe in response to pressure of the shoe thereon to conform to the contour of the shoe, and a holder of substantially triangular shape in which said members are mounted, one of the three sides of said holder being movable relatively to the other two sides to clamp the members in fixed relation to the holder after they have conformed to the contour of the shoe, said movable side having portions arranged to overlap the other two sides to guide it in its clamping movement.
25. 14. In a shoe machine, a shoe rest arranged to engage a shoe on the top of the forepart, said shoe rest comprising a plurality of members relatively movable in response to pressure of the shoe thereon to conform to the contour of the shoe, and a holder of substantially triangular shape comprising parts relatively movable to clamp said members in fixed relation thereto after they have conformed to the contour of the shoe, said holder having means for confining the members in a group of substantially hexagonal form.
30. 15. In a shoe machine, a shoe rest arranged to engage a shoe on the top of the forepart, said shoe rest comprising a plurality of members relatively movable in response to pressure of the shoe thereon to conform to the contour of the shoe, a holder of substantially triangular shape in which said members are mounted, parts of said holder being relatively movable to clamp the members in fixed relation thereto after they have conformed to the contour of the shoe, and a wedge-shaped piece movably mounted in a corner of the holder and slidably in response to the relative movement of said parts to apply clamping pressure to the members.
35. 16. In a shoe machine, a shoe rest arranged to engage a shoe on the top of the forepart, said shoe rest comprising a plurality of members relatively movable in response to pressure of the shoe thereon to conform to the contour of the shoe, a holder of substantially triangular shape in which said members are mounted, one side of said holder being movable relatively to the other two sides to clamp the members in fixed relation to the holder after they have conformed to the contour of the shoe, and wedge-shaped pieces movably mounted in the corners of the holder adjacent to said movable side for applying pressure to the members.
40. 17. In a shoe machine, a shoe rest arranged to engage a shoe on the top of the forepart, said shoe rest being movable heightwise of the shoe in the course of the operation of the machine, and means constructed and arranged to act frictionally on the shoe rest after such movement to hold it against movement in response to pressure of the shoe thereon, said means comprising frictionally engaged surfaces extending in substantially parallel relation to the direction of movement of the shoe rest.
45. 18. In a shoe machine, a shoe rest arranged to engage a shoe on the top of the forepart, said shoe rest being movable heightwise of the shoe in the course of the operation of the machine, and means constructed and arranged to act on the shoe rest at the opposite sides thereof after such movement to clamp and hold it frictionally against movement in response to pressure of the shoe thereon, said means comprising a stationary friction member at one side of the shoe rest and a movable member at the opposite side thereof for forcing it against said stationary member.
50. 19. In a shoe machine, a shoe rest arranged to engage a shoe on the top of the forepart, said shoe rest being movable heightwise of the shoe in the course of the operation of the machine and having thereon a lateral projection provided with converging faces, and a device having faces correspondingly arranged for clamping engagement with said converging faces after such movement of the shoe rest to hold it frictionally against movement in response to pressure of the shoe thereon.
55. 20. In a shoe machine, a shoe rest arranged to engage a shoe on the top of the forepart, said shoe rest being movable heightwise of the shoe in the course of the operation of the machine, clamping means arranged to act on the shoe rest frictionally at one side thereof to hold it against movement, and automatic means for applying pressure to the other side of the shoe rest at a predetermined time in the operation of the machine to force it against said clamping means.
60. 21. In a shoe machine, a shoe rest arranged to engage a shoe on the top of the forepart, said shoe rest being movable into supporting relation to the shoe in the course of the operation of the machine, and means arranged to act on the shoe rest frictionally to hold it against reverse movement, said means comprising a frictionally engaged surface extending in substantially parallel relation to the direction of movement of the shoe rest.
65. 22. In a shoe machine, a shoe rest arranged to engage a shoe on the top of the forepart, said shoe rest being movable into supporting relation to the shoe in the course of the operation of the machine, and automatic toggle-operated means for applying clamping pressure to the shoe rest at a side thereof after its movement into

supporting relation to the shoe to hold it frictionally against reverse movement.

23. In a shoe machine, a shoe rest comprising a group of members relatively movable in response to pressure of a shoe thereon to conform to the contour of the shoe, a movable holder in which said members are mounted, and means for clamping said members in fixed relation to the holder after they have conformed to the contour of the shoe and for also clamping the holder frictionally to prevent movement thereof in response to pressure of the shoe on the members.

24. In a shoe machine, a shoe rest arranged to engage a shoe on the top of the forepart, said shoe rest comprising a group of members relatively movable in response to pressure of the shoe thereon to conform to the contour of the shoe, a movable holder in which said members are mounted, parts of said holder being relatively movable to clamp the members in fixed relation thereto after they have conformed to the contour of the shoe, and means for effecting relative clamping movement of said parts of the holder and for also clamping the holder frictionally to prevent movement thereof in response to pressure of the shoe on the members.

25. In a shoe machine, a shoe rest arranged to engage a shoe on the top of the forepart, said shoe rest comprises a group of members relatively movable in response to pressure of the shoe thereon to conform to the contour of the shoe, a movable holder in which said members are mounted, parts of said holder being relatively movable to clamp the members in fixed relation thereto after they have conformed to the contour of the shoe, a device at one side of the holder for applying pressure thereto to effect relative clamping movement of said parts, and an abutment at the other side of the holder

40

against which the holder is clamped frictionally by said pressure to prevent movement thereof in response to pressure of the shoe on said members.

26. In a shoe machine, a shoe rest arranged to engage a shoe on the top of the forepart, said shoe rest comprising a group of members relatively movable in response to pressure of the shoe thereon to conform to the contour of the shoe, a holder in which said members are mounted, parts of said holder being relatively movable to clamp the members in fixed relation thereto after they have conformed to the contour of the shoe, means for moving the holder toward the shoe, and devices at opposite sides of said holder arranged in cooperative relation to effect relative clamping movement of the parts of the holder and also to clamp the holder frictionally to prevent reverse movement thereof in response to pressure of the shoe on said members.

27. In a shoe machine, a shoe rest arranged to engage a shoe on the top of the forepart, said shoe rest comprising a group of members relatively movable in response to pressure of the shoe thereon to conform to the contour of the shoe, a holder in which said members are mounted, parts of said holder being relatively movable to clamp the members in fixed relation thereto after they have conformed to the contour of the shoe, means for moving the holder toward the shoe, and mechanism constructed and arranged to operate in automatically determined time relation to the movement of the holder to effect relative clamping movement of said parts and also to clamp the holder frictionally to prevent reverse movement thereof in response to pressure of the shoe on said members.
